CENTRIFUGAL SEPARATOR

Wilmer H. Bath, West Conshohocken, Pa., assignor to The Sharples Corporation, Philadelphia, Pa., a corporation of Delaware

Application July 6, 1943, Serial No. 493,651

3 Claims. (Cl. 233—28)

The present invention pertains to the art of centrifugal separators and is concerned with deflector and accelerator arrangements for controlling flow of liquid through such a separator. It is applicable to centrifugal separators of both the so-called "separator" type in which two or more liquids are separated from each other and separately discharged from the influence of centrifugal force and of the clarifier type in which a solid is separated from a liquid and retained in the rotor or discharged separately from the liquid.

In machines of this type, it is common to inject the liquid or mixture of liquids to be treated through a nozzle into the centrifugal rotor and into contact with a deflector member which may be a cone, disc, or other surface designed to cause the liquid to be deflected toward the wall of the rotor, and thereafter to effect acceleration of the liquid by the aid of wings extending longitudinally of the rotor from a zone beyond the zone of deflection toward the zone of discharge from the rotor.

It is frequently desirable, in connection with a centrifugal separator embodying a deflector and a longitudinally extending accelerator as described above, that the deflector be secured to the accelerator member. This is particularly true in cases in which a conical deflector is placed in the path of the injected liquid in order to deflect this liquid with a minimum of turbulence. Considerable difficulty has been encountered in such arrangements in attempting to affix the deflector member to the accelerator in a secure manner, so that these members do not become dislodged from each other in use of the machine and in removal of the unit consisting of the deflector and accelerator for cleaning. A feature of the present invention consists in the fact that it provides a thoroughly satisfactory solution of this problem.

The nature of the problem and of the solution provided by the present invention will be more evident from a reading of the following specification in the light of the attached drawings, in which,

Figure 1 is a cross sectional view, partly in side elevation, illustrating the invention as applied to a centrifugal separator designed to effect centrifugation and separate discharge of a mixture containing a plurality of liquids;

Figure 2 is an enlarged detailed view, partly in cross section and partly in elevation, illustrating the deflector and accelerator of the invention and

the manner of securing these members to each other.

Figure 3 is a detailed side elevation of one wing of the accelerator member in a preliminary stage of the manufacturing process.

Figure 4 is a cross section through the deflector of the invention.

Figure 5 is a side elevation, on an enlarged scale, of a clip used in securing the deflector and accelerator together.

Figure 6 is a cross section on the line 6—6 of Figure 5.

Figure 7 is a cross section on the line 7—7 of Figure 2, and

Figure 8 is a cross section on the line 8—8 of Figure 2.

Referring to the drawings by reference characters, the centrifugal separator may include a frame 10 having a casing 11 for enclosure of the rotor of the machine. The mixture of liquids under treatment is fed to the rotor 20, which rotates within the casing 11. The feed means may be of conventional character, and include a conduit 12 which is attached to a feed nozzle 14 by means of a removable connection 13. The feed and bearing features of the lower end of the rotor may be of any desired type such as the type illustrated in my prior Patent 1,750,154, dated March 11, 1930, for "Centrifugal machine." After being injected into the rotor, the mixture of liquids strikes a deflector cone 15 secured to the lower end of an accelerator member 16, this accelerator member extending upwardly from the longitudinal zone of the cone 15 to the upper end 35 of the rotor. The accelerator member may include a plurality of radially extending wings 17 having flanges secured to each other in the central portion of the rotor by any suitable means, such as rivets 18. The accelerator wings are provided with openings toward their lower ends as indicated at 19 for manipulation by a suitable tool in withdrawing the accelerator and deflector assembly from the rotor for cleaning. The upper end of the rotor 21 is secured through its neck 40 22 to a drive spindle 23 for rotating the rotor. The separated liquid effluents are discharged into covers 24 and 25, respectively.

The features of the centrifugal separator described above are of well known design and form no part of the present invention, since this invention relates to the method of securing the deflector 15 to the accelerator 16. In prior art machines of this type, it has been customary to affix the deflector directly to the accelerator, as by welding or soldering. Such a type of affix-

ment is relatively insecure, however, and is subject to special objection when incorporated in a machine having the features described above by reason of the fact that a careless or inexperienced operator frequently applies the withdrawing tool to the deflector member 15 in removing the deflector and accelerator assembly through the bottom of the rotor for cleaning, and thereby causes breakage of the connection between the members 15 and 16 by such operation.

The manner in which this difficulty has been avoided by the present invention will be evident from consideration of Figures 2 to 8 of the drawings, which illustrate in greater detail the method of securing of the deflector to the accelerator in the practice of the invention. It is believed that the nature of the connection by which the results of the present invention are attained will be best apparent from a preliminary consideration of Figures 3 to 5 of the drawings and the manner in which the parts therein illustrated are secured to each other.

Figure 3 illustrates one wing 17 of the accelerator assembly. The upper portion 26 of this wing is somewhat wider than the radius of the rotor and the lower portion 27 is somewhat narrower than that radius. A slot 28 is provided extending outwardly from the zone of juncture of these upper and lower portions, and a plurality of holes 29 are provided at spaced intervals toward the inner edge 30 of the wing 17 for the securing of rivets, one line of these rivet holes being spaced from the outer edge 31 a distance less than the radius of the rotor and another line of these rivet holes being spaced from that edge a distance greater than the radius of the rotor. A rivet hole or holes 32 is (are) formed in a portion of the lower end 27 of the wing spaced outwardly from the inner edge 33 of that portion.

After the respective wings are manufactured in accordance with the above description, the inner ends of the upper portions 26 of these wings are bent at an angle to the main bodies thereof on a line X—X spaced from the outer edge 31 a distance equal to the radius of the rotor. The angle of the flange formed by this bending operation depends upon the number of wings to be employed in the accelerator unit. If three wings are to be employed, the angle will be 120°, and if four wings are to be employed as illustrated, the angle will be 90°. After the wings are formed and flanged as described above, the deflector member 15 is positioned with respect to one of them. As illustrated in Figure 4, this deflector member comprises a conical base portion 34 connected by an extension or stem 35 with a laterally extending projection or disc 36. The edge of the disc 36 is shaped to fit snugly within the slots 28. In assembling the deflector and accelerator, the projection or disc 36 of the deflector 15 is fitted into the slot 28 of the accelerator, with the conical portion of the deflector extending downwardly therefrom. The companion accelerator wings are then fitted upon the projection or disc 36 with their respective flanges 37 in abutting relation to the inner edges of companion wings as illustrated in Figure 3 of the drawings, and these accelerator wings are then secured to each other by riveting as illustrated in that figure, with the projection or disc 36 of the deflector extension 35 securely held in position within the slots 28.

It will be seen that, by the type of securing described above, the deflector is rigidly held by

the slots 28 in the accelerator wings, with the result that it is impossible to dislodge the deflector from the accelerator.

In order to reinforce the securing effected as described above, I provide a plurality of reinforcing wings secured to the accelerator wings, abutting the upper surface of the deflector 15, and surrounding the extension or neck 35 interconnecting the deflector surface with the projection or disc 36. As illustrated in Figures 5 and 6, each of the reinforcing members constitutes an angular reinforcing member 38 having arms 42 forming an angle with each other similar to the angle formed by the flanges 37 of the wings 17 with respect to their main body portions. The respective arms of these members 38 are each provided with rivet holes 39, and the apex of the angle is curved or cut away at 40 so that these members, when assembled together about the stem or extension 35 snugly surround that member. Each arm 42 of these members 38 is provided with a portion 41 adapted to abut the upper surface 43 of the deflector 15 when the parts are assembled together as illustrated in Figure 2.

In assembling the reinforcing members 38 with the assembled accelerator and deflector, after riveting the accelerator wings together as described above, these reinforcing members are positioned about the stem 35 with their portions 40 abutting the outer surface of that stem, with their portions 41 abutting the upper surface 43 of the deflector 15, and with the rivet holes 39 in their respective arms in line with corresponding rivet holes 32 in the lower portions 27 of the accelerator wings. The reinforcing members are then riveted to the accelerator wings through the rivet holes 32 and 39, as illustrated in Figure 7 of the drawings.

The relationship between the circumference of the disc 36 and the circumference of the deflector base portion 34 is sometimes important, and one feature of the present invention consists in the provision of a disc 36 having a larger circumference than the circumference of the deflector surface. It is sometimes desirable to provide a deflector surface of sufficiently small diameter to prevent projection of the outer surface of the deflector into the rotating body of liquid in the rotor; i. e., to provide a deflector whose circumference does not project outwardly to a zone as far from the center of the rotor as the dam controlling discharge of the lightest liquid from the rotor. It is also frequently desirable that a liquid seal be provided projecting from a central portion of the rotor to a zone within the body of liquid rotating within the rotor. In order to provide such a seal, the disc 36 is designed to dip into the body of liquid rotating within the rotor; i. e., this disc has a circumference extending outwardly within the rotor to a depth beyond the zone of the dam controlling discharge of the lightest liquid from the rotor. Such a feature is not desirable or necessary in connection with all cases of centrifugation, however, and while it forms one aspect of my invention, the invention is not limited thereto.

While the securing of the accelerator wings to each other and to the reinforcing members has been described above as accomplished through riveted connections, it will be evident that welding may be substituted for riveting in accomplishing this securing. While we have described the invention as specifically applied to a deflector having a conical deflecting surface, it will be evident that the invention is applicable to secure-

ment of deflector and accelerator members to each other regardless of the specific shape of the deflector surface. Similarly, the invention is not limited to any specific form of longitudinally extending accelerator member, as it may be applied in connection with accelerator members having varying shapes or varying numbers of wings or accelerator blades.

Various other modifications are possible within the scope of the invention, and I do not therefore wish to be limited except by the scope of the following claims.

I claim:

1. In a centrifugal separator, the combination comprising a centrifugal rotor, means for injecting liquid into the rotor, a deflector member in the path of the injected liquid, a longitudinally extending accelerator extending beyond said deflector in the direction of flow of liquid through said rotor, said accelerator comprising a plurality of wings, an extension from said deflector member interconnecting the same with said accelerator, and a laterally extending enlargement on a portion of said extension secured within a corresponding laterally extending recessed portion of said accelerator member, said accelerator wings being secured together in their central portions and thereby clamping said enlargement therebetween.

2. In a centrifugal separator, the combination comprising a centrifugal rotor, means for injecting liquid into the rotor, a deflector member in the path of the injected liquid, a longitudinally extending accelerator extending beyond

said deflector in the direction of flow of liquid through said rotor, said accelerator comprising a plurality of wings, an extension from said deflector member interconnecting the same with said accelerator, a circular disc constituting a laterally extending enlargement on said extension, said circular disc being mounted in a corresponding laterally extending recessed portion of said accelerator member, and said accelerator wings being secured together in their central portions and thereby clamping said disc therebetween.

3. In a centrifugal separator, the combination comprising a centrifugal rotor, means for injecting liquid into the rotor, a deflector member in the path of the injected liquid, a longitudinally extending accelerator extending beyond said deflector in the direction of flow of liquid through said rotor, said accelerator comprising a plurality of wings, an extension from said deflector member interconnecting the same with said accelerator, a circular disc constituting a laterally extending enlargement on said extension, said circular disc being mounted in a corresponding laterally extending recessed portion of said accelerator member, and said accelerator wings being secured together in their central portions and thereby clamping said disc therebetween in said recessed portion, said disc extending outwardly from a central portion of the rotor to a zone radially beyond the outermost portion of said deflector member.
